[**] Term: 14 Years

[57] CLAIM

The ornamental design for a nipple for premature infants, or the like, substantially as shown and described.

[21] Appl. No.: 30,190

DESCRIPTION

[22] Filed: Apr. 16, 1979

FIG. 1 is a front perspective view of a premature infant nipple; showing my new design;
 FIG. 2 is a front elevation view thereof;
 FIG. 3 is a top plan view thereof;
 FIG. 4 is a bottom plan view thereof;
 FIG. 5 is a left-side elevation view of FIG. 2;
 FIG. 6 is a right-side elevation view of FIG. 2; and
 FIG. 7 is an elevation view of FIG. 2 from the back.
